INTERVAL TIMER

Helmut D. Beerbaum, New Haven, Conn., assignor to Robertshaw Controls Company, Richmond, Va., a corporation of Delaware

Filed Feb. 10, 1965, Ser. No. 83,764

Term of patent 14 years

(Cl. D42—7)

Fig. 2

FIG. 1 is a top plan view of an interval timer, showing my new design; and

FIG. 2 is a side elevational view thereof.

I claim:

The ornamental design for an interval timer, substantially as shown.
